UNITED STATES PATENT OFFICE

JACOBUS PAULUS VAN GASTEREN, OF HAARLEM, NETHERLANDS

FASTENING DEVICE FOR WRITING UTENSILS, SUCH AS PENCILS OR THE LIKE

Application filed May 1, 1931. Serial No. 534,406, and in the Netherlands April 16, 1930.

The invention relates to a device for fastening (tying-up) a writing utensil, such as a pencil or the like, by means of a flexible string, wire or like fastening-means, which, 5 after having been unwound from a spring-actuated-drum, may be wound up again on said drum.

By the known devices of this kind a pull is exerted continuously on the pencil or pen-holder during writing via the fastening-means by the spring-actuated-winding-drum, which is very objectionable.

The chief object of this invention is to overcome this disadvantage and with this object 15 in view the invention consists herein, that a support for the writing-utensil is provided with a resiliently upwards pressed holder, which, when pressed downwards, makes a clamping-device for the fastening-means in- 20 operative, which device is such, that when the fastening-means is being unwound it lets same pass unobstructedly but thereafter clamps it tightly.

If one wants to use the pencil or the like 25 the fastening-means is unwound from the drum, whereupon it is immediately automatically clamped, so that a pull no longer is exerted on the writing-utensil, while when the pencil or the like thereafter is pressed on 30 its holder, the clamping-device of the string or the like automatically is made inoperative, whereby the latter is wound up immediately.

The drawings represent by way of example 35 a constructional form of the fastening-device according to this invention. In the drawings the whole device is arranged on and in a loose wooden block, on the upper face of which the pencil is put. It is, however, to be understood, that the device quite as well can 40 be arranged on or in all kinds of devices in which it is desired to have a pencil or the like always ready at hand, such as in writing-desks, writing-money-chests, etc.

In the drawings:

Fig. 1 is a side elevation, partially a section, and Fig. 2 is a bottom plan view of the principal part of the device.

a represents a wooden-block, provided with a recess *b*. On the top-face of this block a small cover-plank *c* is fixed, on which two

resilient (flexible) clips *d* and *e* for the pencil are arranged and into an opening of which a sleeve *f* is inserted, through which the string *g*, which is secured to the pencil, leads to the spring-actuated-winding-drum *h*, 55 located in said recess *b*. This winding-drum *h* is known on its own and also in known manner it is enclosed within a cylindrical box or casing with an opening through which the string *g* extends.

Further the clamping-device for the string is located in the recess *b* of the wooden block and said device consists of a suitably bent plate *j*, over which the string runs and which is provided with two depending legs *k*, between which a lever *m*, one arm of which is loaded by a small weight *l*, is pivotally mounted.

Said lever *m* further is designed and arranged such, that when the whole device is 70 in the normal position, the lever with its loaded arm, assisted by the tension in the string, rigidly clamps said string against the plate *j*, in such a way though, that when the string is drawn out, same can pass un- 75 restrictedly between the plate *j* and said lever arm, since the latter then is lifted a little.

The other arm of lever *m* extends under the pencil-clip *e*, which clip is movable up- and downwards in a sleeve *n*, arranged in a 80 hole of the cover-plank *c* and in which a screw-spring *o* is located, so that clip *e* is normally pressed upwards. An extension *p* of clip *e* extends right above and very near to but not in contact with the latter arm 85 of lever *m*.

It is clear now, that when the pencil has been used and the string is in the unwound position one can make the string wind up 90 automatically by pressing the pencil in the clips *d* and *e*, since clip *e* then presses the right hand arm of lever *m* downwards and consequently the left hand one moves upwards, whereby the string *g* is released, so 95 that by the spring-actuated-drum it is drawn inwards.

On top of the wooden block further is arranged a sleeve *q*, into which a penholder or the like can be inserted; it is clear, how- 100

ever, that this sleeve has nothing common with the invention proper.

Further in the bottom of the block an iron or lead plate *r* is fitted in order to hold the 5 complete device, so that same, when the pencil is taken from its supporting place, better remains on the spot.

It is to be understood that the device illustrated in the drawings only represents one of 10 the many forms in which the invention can be embodied and actually represents such a form suitable to be used as a separate unit on writing desks and the like on which, if desired, it can be rigidly secured by means of screws 15 or the like and that many alterations are possible within the scope of the invention as indicated in the claim, e. g. the small weight *l*, which tends to draw lever *m* in the operative position in which it clamps string *g* between 20 one of its arms and the suitably bent plate *j*, might be replaced by a suitable screw- or other-spring performing the same action.

What I claim is:

Fastening apparatus for an intermittently 25 used article, comprising in combination with a spring-actuated drum and a cord thereon attached to the article, means to normally clamp the cord, a downwardly movable holder for the article, and a spring to normally raise 30 said holder, the said holder having means, active when the holder is depressed, to cause the clamping means to release the cord and allow the cord to be rewound upon the drum.

In testimony whereof, I have signed my 35 name to this specification.

JACOBUS PAULUS VAN GASTEREN.
